(57) **CLAIM**

The ornamental design for a product traceability robot as shown and described.

DESCRIPTION

FIG. 1 is a top, front and right perspective view of a product traceability robot showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings are for illustrative purposes and represent unclaimed portions of the product traceability robot and therefore form no part of the claimed design. Unshaded portions between solid and broken lines represent unclaimed portions and therefore form no part of the claimed design.
